UNITED STATES PATENT OFFICE.

ROBERT W. WHITSELL AND CHARLES B. WARD, OF PALISADE, NEBRASKA.

HORSE-COLLAR.

No. 890,478.

Specification of Letters Patent.

Patented June 9, 1908.

Application filed June 29, 1907. Serial No. 381,464.

To all whom it may concern:

Be it known that we, ROBERT W. WHITSELL and CHARLES B. WARD, citizens of the United States, residing at Palisade, in the 5 county of Hitchcock and State of Nebraska, have invented new and useful Improvements in Horse-Collars, of which the following is a specification.

This invention relates to a horse collar and 10 more particularly to a reinforcing attachment to be applied thereto for preventing the collar from breaking at the bottom or breast portion.

The invention has for one of its objects to 15 provide an attachment or reinforce of the character referred to that is adapted to be applied to the hames-engaging roll of the collar. At the breast portion of the latter, the said attachment being preferably of spring 20 metal so as to permit the collar to be readily opened for placing it on or taking it off the horse. In this connection, it may be remarked that in manipulating a collar, it is the common practice to take hold of one side 25 of the collar and allow the other to hang loosely while placing the collar on or taking it off the horse, and the weight of the loose side of the collar has a destructive effect at the neck portion, tearing the padding and 30 stitching, thereby rendering the collar useless. With the reinforce attachment above referred to, this difficulty is effectively overcome.

A further object of the invention is to provide 35 a reinforce composed preferably of a single piece of metal possessing resiliency so as to constitute a spring, the reinforce having spring clip portions that are adapted to be gripped over the hames-engaging roll of 40 the collar when the reinforce is used as an attachment or adapted to be embedded in the said roll when the reinforce is used as a permanent part of the collar and incorporated in the latter during the manufacturing 45 thereof.

With these objects in view and others, as will appear as the description proceeds, the invention comprises the various novel features of construction and arrangement of 50 parts which will be more fully described hereinafter and set forth with particularity in the claims appended hereto.

In the accompanying drawing, which illustrates 55 certain embodiments of the invention, Figure 1 is a front view of a collar showing the reinforcing device attached thereto.

Fig. 2 is a transverse section on line 2—2, Fig. 1. Fig. 3 is a front view of the reinforcing device detached. Fig. 4 is a sectional view on line 4—4, Fig. 3. Fig. 5 is a front view of 60 a collar manufactured with the reinforcing device as a part thereof. Fig. 6 is a section on line 6—6, Fig. 5.

Similar reference characters are employed to designate corresponding parts throughout 65 the several views.

Referring to the drawing, A designates a horse collar of ordinary construction to which is applied the reinforcing device designated generally by B. This device preferably comprises a single piece of resilient metal that is bent in the form of a U to correspond to the breast portion of the hames-engaging roll 1 of the collar, and more specifically is composed of a metal strip 2 of approximately semi-circular 70 form and of curved cross-section, the ends of the strip being enlarged into spring clips 3 that are adapted to be engaged over the roll 1 of the collar and at the center of the strip is another spring clip 4 also for engaging 75 the said roll. At the central clip 1 is an apertured lug 5 that serves to receive a fastening such as a rivet 6 for securing the attachment to the collar, as shown in Fig. 1 and holding the same centrally thereon. At the terminal 80 clips 3 are laterally-extending lugs 7 that bear against the front side of the shoulder portions 8 of the collar and coöperate to hold the attachment in place. In the opening of the collar for applying it to a horse or taking 85 it off, the portions of the attachment between the end and central clips can be flexed without, however, permitting the collar to be opened to such a point as to break the breast portion thereof.

The attachments are manufactured preferably in the form shown in Fig. 3, so that they can be applied to horse collars already in use, but if it is desired to incorporate the reinforcing devices in the collars during manufacturing, these attachments can be employed in the manner shown in Figs. 5 and 6, it being merely necessary to turn the lugs or ends of the clips inwardly so as to form a circle to correspond with the shape of the roll of the 95 collar.

From the foregoing description, taken in connection with the accompanying drawing, the advantages of the construction and of the method of operation will be readily apparent 100 to those skilled in the art to which the invention appertains, and while I have described

the principle of operation of the invention, together with the device which I now consider to be the best embodiment thereof, I desire to have it understood that the device 5 shown is merely illustrative and that such changes may be made when desired, as are within the scope of the claim.

Having thus described the invention, what I claim is:—

- 10 An attachment for horse collars comprising a reinforcing device in the form of a curved strip of spring metal, terminal and

central roll-engaging clips, and bendable lugs on the strip adapted to be turned inwardly to meet the ends of the clips or outwardly in the 15 opposite direction from the clips.

In testimony whereof, we affix our signatures in presence of two witnesses.

ROBERT. W. WHITSELL.
CHAS. B. WARD.
